UNITED STATES PATENT OFFICE

CHARLES V. HALLENBECK, OF RIFLE, COLORADO

HOISTING APPARATUS

Application filed February 25, 1928. Serial No. 256,938.

This invention relates to a hoisting apparatus and pertains particularly to an apparatus of this kind especially designed and adapted for use in connection with a dumping vehicle body of a vertical swinging type, and it is an object of the invention to provide an apparatus of this kind comprising uprights or standards mounted in a manner to permit such uprights or standards to be set up against the seat structure or cab and also to dispose the weight imposed thereon direct to the vehicle frame.

It is also an object of the invention to provide an apparatus of this kind comprising a plurality of uprights or standards adapted to be supported by the frame of a vehicle for swinging movement and wherein the mechanism associated with such uprights or standards is such to permit said uprights or standards to be selectively spaced apart to compensate for various widths of vehicle frames whereby the apparatus constitutes what may be termed a "universal unit" as the same may be applied to various vehicle frames without special construction.

A still further object of the invention is to provide an apparatus of this kind comprising means whereby the same may be properly installed without requiring drilling of holes for the use of bolts or the like through the truck frame together with means for maintaining taut the cable or cables comprised in the apparatus.

An additional object of the invention is to provide an apparatus of this kind with a double or two-way cable wind-type operating to raise or lower the vehicle body as desired and which also operates to hold such body firm to its position at all times and tying it rigid to the truck when the body is in its lowermost position.

It is also an object of the invention to provide an apparatus of this kind which is mounted and applied in a manner which eliminates rattling or vibration of the body when running without load or to kick-up while loading heavy articles at the tail end portion thereof.

The invention consists in the details of construction and in the combination and ar-

angement of the several parts of my improved hoisting apparatus whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in front elevation of a hoisting apparatus constructed in accordance with an embodiment of my invention, the side members of the vehicle frame being shown in section and a coacting dump body being diagrammatically indicated by broken lines;

Figure 2 is a view in side elevation of the apparatus, the position of the uprights as illustrated in Figure 1 being indicated by broken lines, a second position of said uprights being indicated in full lines with the dump body in fragment together with the associated part of the vehicle frame and cab;

Figure 3 is an enlarged fragmentary view in front elevation illustrating the mounting for one of the uprights or standards as herein disclosed;

Figure 4 is a vertical sectional view taken substantially central of Figure 3.

As disclosed in the accompanying drawings, 1 denotes the side members of a vehicle frame with which has substantially direct contact a dumping body B when in its normal or working position as is particularly set forth in my application for patent executed on even date herewith.

The forward portions of the side members 1 support a conventional seat structure or cab C and when the body B is in its lowered or working position, the forward end of said body B closely approaches the rear of the cab C as illustrated in Figure 1 but leaving a slight space therebetween.

Mounted upon the members 1 in transverse alignment and immediately adjacent to the rear of the cab C are the bearing sleeves 2 each being mounted upon and integrally con-

nected with a base plate 3. The outer marginal portion of each of the plates 3 has direct contact from above with the upper and inwardly disposed flange 1^a of a member 1 and is held thereto by a clamping plate 4. This plate 4 underlies the plate 3 with a portion underlying the flange 1^a. Coacting with the inner portions of the plates 3 and 4 are the clamping bolts 5 which, upon proper manipulation, effect the desired and secure anchoring of a plate 3 to a side member 1. The portion of the plate 4 underlying the flange 1^a has threaded therethrough from below a binding screw 6 for contact with the flange 1^a to provide further means for maintaining the plate 3 in applied or working position.

Snugly fitting within the bearing sleeve 2 is a sleeve 7 to which is welded the lower end portion of a standard or upright 8. As 20 herein disclosed, this standard or upright 8 is of channel formation and each of its side flanges 8' has its lower portion cut away in a manner to assure close contact of the standard or upright 8 with the peripheral surface of 25 the sleeve 7. It is to be further noted that when the standard or upright 8 is in substantially a vertical position, said standard or upright is arranged substantially entirely to one side of the vertical radius of the sleeve 7 and with the lower portion of the standard or 30 upright 8 in direct contact for a distance substantially one-quarter around the periphery of the sleeve 7.

Snugly engaged within the sleeve 7 is a 35 bushing 9 of bronze or other desired material and directed through this bushing 9 is a transversely disposed winding shaft S. This shaft S is common to the mountings for both of the standards or uprights 8.

40 This particular mounting of each of the bearings 2 and the connection therewith of an upright or standard 8 is such to impose all load carried by the upright or standard together with the weight thereof directly to 45 the side members 1 and free of the shaft S so that said shaft S may be rotated when desired with a minimum of resistance.

The forward upper portion of the wall of 50 each of the bearings 2 is cut out, as at 10, to permit the desired connection of an upright or standard 8 with a sleeve 7 and to permit such upright or standard to have requisite swinging movement within the bearing 2 as required upon the desired lifting of the 55 body B.

The sleeve 7 carries an upstanding tube 11 directed through the wall of said sleeve and which is provided at its outer end with suitable means, as at 12, to permit coupling 60 therewith of a grease gun or alemite nozzle so that suitable lubricant may be applied. The bushing 9 together with the sleeve 7 are also provided therethrough at suitable points with the openings 14 to facilitate the proper 65 application or distribution of such lubricant.

The lower portion of each of the standards or uprights 8 carries a rearwardly directed plate 15, the outer portion of which is disposed on such curvature as to have close contact with the periphery of the bearing 2 which is cylindrical in cross section. This plate 15 serves to substantially close the cut out portion 10 of the bearing 2 and especially when the standard or upright is in its normal vertical position. The tube 11 is also disposed through this plate 15.

The shaft S extends outwardly beyond the bearings 2 and each of said extended portions constitutes a winding drum 16 with which contacts an end portion of a winding cable 17. 80 One end portion of this cable 17 is secured or connected to the drum 16 in any desired manner. This cable 17 extends upwardly and over a pulley 18 freely mounted on an end portion of a shaft 19 which is freely directed through the bearings 20 carried by the upper end portions of the uprights or standards 8. The cable 17 then extends downwardly from the pulley 18 and is operatively connected, as at 21, with the lower portion of a leg 22 depending from the forward end portion of the body B.

One extended end portion of the shaft S outwardly of the drum 16 is provided with a suitable mechanism, generally indicated at 23, for rotating the shaft S as desired to effect the desired raising and lowering of the forward end portion of the body B, said mechanism 23 being also adapted for manual operation through the medium of a hand crank 24, 100 although it is to be understood that if desired suitable power operating means may be provided.

Each of the bearings 20 is carried by a 105 plate 25 slidably held to the upper portion of an upright or standard 8 by the bolts 26 or the like directed through a suitably positioned slot 27 in the upright or standard 8 and the lower portion of the plate 25 carries an outstanding lug 28 with which directly contacts from below a shank 29. This shank 29 is freely directed through a cross plate 30 carried by the upper portion of the upright or standard 8 and threaded upon said shank 29 above and below the plate 30 are the holding nuts 31. By proper manipulation of the nuts 31 the plate 25 may be adjusted as desired in a direction lengthwise of the upright or standard 8 to maintain taut the cable 17 and thus assuring maximum efficiency of 110 the apparatus.

It is to be noted that the pulleys 18 are freely mounted upon the shaft 19 so that there will be a relative independent rotation of such pulleys and which is desirable in 115 the event of lateral turning or displacement of the body B during either a lifting or lowering movement. It is also to be noted that the shaft 19 is freely directed through the bearings 20 so that in the event either or 120

both of the pulleys should bind upon the shaft 19, said shaft will be capable of rotation and thus assuring the continued effective operation of the apparatus.

5 When the body B is in its lowered position, the uprights 8 are substantially vertically disposed and each of such uprights or standards 8 at its upper portion contacts with a cushion 32, preferably rubber, suitably affixed to the rear wall of the cab C.

10 The central portion of the shaft S has fixed thereto a drum 33 upon which wind the opposite end portions of a cable 34, said end portions of the cable 34 winding upon the drum 33 in a direction reverse to the winding of the cable 17 so that as the cable 17 so winds upon the drum 16 to raise the body B the cable 34 will correspondingly unwind and vice versa.

15 20 The central portion 34' of the cable 34 constitutes a loop which is operatively engaged, as at 35, at a suitable point to the front end of the body B so that when the body B is in its lowered position the cable 34 serves to tie the body B rigid to the vehicle or truck frame, thus preventing rattling or vibration of the body when the vehicle is running without load and also to prevent the body from kicking up while loading heavy articles into the 25 30 body through the tail end thereof. The cable 34 also serves in connection with the cable 17 to hold the body B firm to its position at all times.

It is also to be noted that the pulleys 18 are 35 rearwardly offset with respect to the uprights or standards 8 and this arrangement causes the body B when in lowered position to crowd the cables 17, thus pushing the uprights or standards 8 close against the cushions 32 40 and maintaining said uprights or standards rigid in their substantially normal vertical positions. This is allowed in view of the fact that the uprights or standards 8 are disposed between the forward end of the body B and the cab C, the spacing between said forward 45 end of the body B and the cab C when the body B is in its lowered position being sufficient to accommodate the uprights or standards.

50 It is also to be noted that the flanges 8' terminate a desired distance inwardly of the upper or outer ends of the uprights or standards 8 in order to offer no hindrance or obstruction to the desired adjustments of the 55 plates 25.

From the foregoing description it is thought to be obvious that a hoisting apparatus constructed in accordance with my invention is particularly well adapted for use 60 by reason of the convenience and facility with which it may be assembled and operated, and it will also be obvious that my invention is susceptible of some change and modification without departing from the principles 65 and spirit thereof and for this reason I do

not wish to be understood as limiting myself to the precise arrangement and formation of the several parts herein shown in carrying out my invention in practice except as herein-after claimed.

I claim:—

1. In combination with a vehicle frame and an associated vertical swinging dumping body, bearings mounted upon the frame at opposite sides thereof, sleeves snugly engaged within the bearings for rocking movement, uprights, each upright having its lower end portion connected directly to one of the sleeves, the coacting bearing having a portion cut away to permit such connection and to allow the upright to have requisite movement with the sleeve, a shaft disposed through the sleeves of both bearings, cables connected to the body and winding upon the shaft, pulleys carried by the upper portions of the uprights over which the intermediate portions of the cables travel, and means for rotating the shaft independently of the sleeves for winding the cables upon the shaft to lift the body.

2. In combination with a vehicle frame and an associated vertical swinging dumping body, bearings mounted upon the frame at opposite sides thereof, sleeves snugly engaged within the bearings for rocking movement, uprights, each upright having its lower end portion connected directly to one of the sleeves, the coacting bearing having a portion cut away to permit such connection and to allow the upright to have requisite movement with the sleeve, a shaft disposed through the sleeves of both bearings, cables connected to the body and winding upon the shaft, pulleys carried by the upper portions of the uprights over which the intermediate portions of the cables travel, means for rotating the shaft independently of the sleeves for winding the cables upon the shaft to lift the body, and a second shaft freely supported by the upper portions of the uprights, said pulleys being freely mounted upon said second shaft.

3. In combination with a vehicle frame and an associated vertical swinging dumping body, bearings mounted upon the frame at opposite sides thereof, sleeves snugly engaged within the bearings for rocking movement, uprights, each upright having its lower end portion connected directly to one of the sleeves, the coacting bearing having a portion cut away to permit such connection and to allow the upright to have requisite movement with the sleeve, a shaft disposed through the sleeves of both bearings, cables connected to the body and winding upon the shaft, pulleys carried by the upper portions of the uprights over which the intermediate portions of the cables travel, means for rotating the shaft independently of the sleeves for winding the cables upon the shaft to lift

the body, and an additional cable operatively engaged with the body and winding upon the shaft upon rotation of the shaft to wind the first named cables, said last named cable winding upon the shaft in a direction reverse to the winding of the first named cables.

4. In combination with a vehicle frame and an associated vertical swinging dumping body, bearings mounted upon the frame at opposite sides thereof, sleeves snugly engaged within the bearings for rocking movement, uprights, each upright having its lower end portion connected directly to one of the sleeves, the coacting bearing having a portion cut away to permit such connection and to allow the upright to have requisite movement with the sleeve, a shaft disposed through the sleeves of both bearings, cables connected to the body and winding upon the shaft, pulleys carried by the upper portions of the uprights over which the intermediate portions of the cables travel, means for rotating the shaft independently of the sleeves for winding the cables upon the shaft to lift the body, a base plate for each of the bearings, and means for clamping said base plate to the frame for holding the bearing in applied position thereon, said clamping means avoiding penetration through the members of the frame to which the bearing is clamped.

5. In combination with a vehicle frame and an associated vertical swinging dumping body, bearings mounted upon the frame at opposite sides thereof, sleeves snugly engaged within the bearings for rocking movement, uprights, each upright having its lower end portion connected directly to one of the sleeves, the coacting bearing having a portion cut away to permit such connection and to allow the upright to have requisite movement with the sleeve, a shaft disposed through the sleeves of both bearings, cables connected to the body and winding upon the shaft, pulleys carried by the upper portions of the uprights over which the intermediate portions of the cables travel, means for rotating the shaft independently of the sleeves for winding the cables upon the shaft to lift the body, and means carried by each of the uprights for substantially closing the cut out portion of the bearing when the body is in its lowered position.

6. In combination with a vehicle frame and an associated vertical swinging dumping body, bearings mounted upon the frame at opposite sides thereof, sleeves snugly engaged within the bearings for rocking movement, uprights, each upright having its lower end portion connected directly to one of the sleeves, the coacting bearing having a portion cut away to permit such connection and to allow the upright to have requisite movement with the sleeve, a shaft disposed through the sleeves of both bearings, cables connected to the body and winding upon the shaft, pul-

leys carried by the upper portions of the uprights over which the intermediate portions of the cables travel, means for rotating the shaft independently of the sleeves for winding the cables upon the shaft to lift the body, said pulleys being offset with respect to the uprights in a direction toward the body to permit the forward end of the body to crowd the cables to hold the uprights in vertical position when the body is lowered.

In testimony whereof I hereunto affix my signature.

CHARLES V. HALLENBECK.
